United States Patent Office

Des. 181,295
Patented Oct. 29, 1957

181,295

LINK CHAIN FOR A NECKLACE OR THE LIKE

Adolph Katz, Providence, R. I., assignor to Coro, Inc.,
New York, N. Y., a corporation of New York

Application April 23, 1957, Serial No. 45,853

Term of patent 7 years

(Cl. D45—16)

Fig. 1

Fig. 2

Fig. 1 is a plan view of a link chain for a necklace or the like, showing my new design.

Fig. 2 is an edge view thereof.

I claim:

The ornamental design for a link chain for a necklace or the like, substantially as shown.
